UNITED STATES PATENT OFFICE.

CHARLES E. THOMPSON, OF TROY, NEW YORK, ASSIGNOR TO LUXURY SALES COMPANY,
OF TROY, NEW YORK, A CORPORATION OF NEW YORK.

DESIGN FOR A SHAVING-BRUSH.

42,120.

Specification for Design.

Patented Jan. 30, 1912.

Application filed April 19, 1911. Serial No. 622,170. Term of patent 14 years.

To all whom it may concern:

Be it known that I, CHARLES E. THOMPSON, a citizen of the United States, residing at Troy, in the county of Rensselaer and State of New York, have invented a new, original, and ornamental Design for a Shaving-Brush, of which the following is a specification, reference being had to the accompanying drawing, forming a part thereof.

The single figure of the drawing is a view

in perspective of a shaving-brush embodying my design.

I claim:

The ornamental design for a shaving-brush as shown.

CHARLES E. THOMPSON.

Witnesses:

R. A. LEDUC,
J. E. DONSBACH.
